UNITED STATES PATENT OFFICE

141,459

DESIGN FOR A PLATE OR SIMILAR ARTICLE

Mabel C. Ruskin, Abingdon, Va.

Application June 1, 1944, Serial No. 113,832

Term of patent 14 years

(Cl. D44—15)

To all whom it may concern:

Be it known that I, Mabel C. Ruskin, a citizen of the United States, residing at Abingdon, in the county of Washington and State of Virginia, have invented a new, original, and ornamental Design for a Plate or Similar Article, of which the following is a specification, reference being had to the accompanying drawing, forming part thereof.

Figure 1 is a top plan view of a plate, or similar article, showing my new design, a repeat unit of which is contained between the dotted lines.

I claim:

The ornamental design for a plate or similar article, as shown and described.

MABEL C. RUSKIN.
